14 Claims. (Cl. 200—149)

The invention relates to an electric circuit-breaker having means for extinguishing the arc by a pressure medium, in particular gas or vapour, of the kind in which the pressure is produced by the arc itself in a closed and preferably tubular chamber.

In the known circuit-breakers of this kind the extinction of the arc is effected by the blast of an extinguishing medium which flows under pressure. It is the more effective the higher the pressure of the blast gas. The pressure of the gas is the higher the greater the quantity of energy of the arc which is used for the development and heating of the gas (energisation). It is, therefore, difficult to break a circuit in which a small current is flowing because in this case the energy of the arc is not sufficient for producing the necessary pressure of the blast gas in the relatively large switch chamber. The minimum dimensions of the switch chamber are limited by the dimensions of the electrode which is moved through the chamber, and for its part cannot be reduced below a certain size for reasons of mechanical strength and by reason of the current which has to be conducted through it.

According to the present invention, a circuit-breaker of the aforesaid type is improved by the arrangement of a separate insulating piece or filling piece which reduces the cross-sectional area of the switch chamber in comparison with the internal area determined by the outer periphery of the movable electrode.

By this means not only is the pressure produced in the case of small currents increased owing to the reduction in the volume of the switch chamber, but the surface which is exposed to the arc is also increased in proportion to the cross-section, so that the arc comes into intimate contact with the surfaces which cool and de-ionise it. It is particularly advantageous to make the insulating filling pieces, and in some cases also the walls of the switch tube, of materials which give off gas or vapour under the effect of the arc such, for example, as vulcanite or fibre, since the increase in pressure then becomes still greater.

By means of the invention it is possible when disconnecting circuits carrying small currents to provide a narrow passage for the arc although the switch member has a cross-section of sufficient area for conducting large currents. Then, a switch having a single point of break and able to break a circuit carrying a large current can also be used for breaking a circuit carrying quite a small current. If the narrow passage through which the arc is drawn is provided, in accordance

with a further feature of the invention, with a movable wall which, in the case of large currents, enables the passage to be enlarged owing to the pressure of the arc, then the switching range becomes particularly large.

For an effective extinction of the arc, in addition to the above-mentioned conditions, the following condition must also be fulfilled in a circuit-breaker in accordance with the present invention:—

As great a part of the arc as possible must be situated in the narrow switch chamber since the voltage gradient of the arc is high along the narrow switch chamber, and the arc effects the development of gas along the entire chamber.

In one form of construction in which these conditions are very largely fulfilled, the circuit-breaker consists of a tube of insulating material (switch tube) which represents the outlet passage of a closed auxiliary chamber which is employed for accumulating the blast gas under pressure. The switch tube and auxiliary chamber define what might be conveniently termed a blind passage. The fixed contact is located in this auxiliary chamber. The movable contact member closes the opening in the tube when in the switched-in position and also during the first part of the disconnecting process. After the contacts have been separated the arc is drawn by the switch member into the switch tube. An insulating piece following the switch member moves out of the auxiliary chamber axially into the tube. The switch chamber which has now been formed and of which the walls are formed by the switch tube and the insulating piece introduced therein, can be so shaped, entirely independent of the cross-section of the switch member, that small and even the smallest currents can be extinguished with certainty. On the further movement of the switch member it moves out of the tube and suddenly frees the entire cross-section of the narrow switch chamber for the passage of the blast. The intensive blast which now follows, owing to the energy of the stored gas under pressure, effects the extinction of the arc during the first passage of the current through zero. If the filling piece is suitably dimensioned an arrangement of this nature results in favourable conditions for extinguishing the arc for currents of all magnitudes from zero onwards.

Various constructional embodiments of circuit-breakers in accordance with the invention are illustrated by way of example in the accompanying drawings in which:—

Figure 1 is a longitudinal section through a circuit-breaker in accordance with the invention.

Figure 2 is a further form of construction, also in section, of a circuit-breaker in accordance with the invention which is suitable in particular for switches separating under load.

Figure 3 is a section through the switch chamber and the switch pin of a third form of construction.

10 Figure 4 is a modification of the form of construction shown in Figure 2.

Figure 5 is a section on the line I—I through the filling piece connected with the switch pin.

15 Figure 6 is a modification of the form of construction according to Figure 3 having a stationary filling piece.

Figure 7 is a further improved form of construction of a circuit-breaker in accordance with the invention.

20 Figure 8 is another form of construction having a damping resistance.

Figure 9 shows another form of construction of a switch chamber which, of course, may be used in any of the other circuit-breakers shown.

25 Figure 10 is a modification of the form of construction shown in Figure 9.

Figure 11 is a form of construction in which the switch pin is fixed and in which the switch chamber is movable together with the counter contact located in it.

30 Figure 12 is a form of construction in which separate additional gases are employed and in which the switch chamber is provided with a separate outlet opening for the blast gases.

35 Figure 13 is a view, partly in section and partly in plan, showing a circuit-breaker with two break points connected one after the other and of column-like construction, and

40 Figure 14 is a circuit-breaker of column-like construction which is particularly suitable for high voltages and not very great currents.

Referring to Figure 1 of the drawings, the reference numeral 1 represents the stationary contact and 2 the pin-like movable contact of the circuit-breaker. The contact 1 is fixed in a cylindrical metal casing 3 which carries one of the terminals 4. An insulator 5 forms the switch chamber and carries at the same time the contact-making device. The circuit-breaker is shown fixed by means of a base plate 6 to a wall but any other suitable form of fastening could be employed instead of that shown. The insulator 5 is provided with a tubular part 7 in which the switch pin 2 moves with only a little play. The hollow chamber 8, which is herein-after also termed the auxiliary chamber, acts as a chamber for accumulating the gas under pressure produced by the arc and defines with the switch tube 7 a blind passage. In the cylindrical part 3 is arranged a pin 9 which is made of insulating material and under the action of the springs 10 follows the contact 2 during its disconnecting movement. The pin 9 acts as a filler for the switch tube 7 and reduces the cross-section of this tube when the contact 2 has moved out. The diameter of the filling piece 9 is slightly less than that of the contact 2 and the piece itself is preferably made of a material which gives off gas or vapour when acted upon by the arc, for example a material such as vulcanite or fibre. It is preferable to keep the difference in diameter as small as possible in order that the gap in which the arc burns may be as narrow as possible. The narrowness of the gap is limited only by the condition that the filling piece

must be able to move with ease in the tube 7. The gases and vapours which escape from the switch chamber are led away through the passage 11. The passage is turned through an angle of about 180° in order that no gases may reach the parts situated below the switch chamber.

The pin contact 2 slides in a sliding contact 12 which is mounted on a metal plate or support 13 to which the second terminal 14 is connected. 10 The part 13 is fixed to the base plate 6 by means of an insulator 15. On the base plate 6 is also mounted a lever 16 by which the contact 2 is operated and of which its shaft 17 is moved by any suitable form of driving mechanism which 15 is not illustrated in the drawings. The insulator 18 which carries the switch chamber 5 may be made in one piece with the latter as illustrated or may consist of a separate part as is shown in Figure 2.

20 The method of operation of the apparatus is as follows. When the circuit-breaker is connected, the current flows from the terminal 4 through the metal body 3 to the fixed contact 1 and passes thence to the pin contact 2 through 25 the sliding contact 12 and the supporting member 13 to the terminal 14.

When, on breaking the circuit, the contact 2 is moved downwards, the arc formed between the contacts 1 and 2 heats the air in the chamber 8 30 so that the pressure in this chamber is increased to a certain extent. The contact 2 then draws the arc downwards into the tube 7 whereby the pressure is still further increased particularly if the walls of this tube are made of a material 35 which gives off gas or vapour on being heated. When the contact 2 comes out of the tube 7 a stream of compressed gas follows the contact 2 whereby if the pressure is sufficient the arc is extinguished. The gases then escape through 40 the passage 11.

With the arrangement which has just been described, if a circuit carrying a small current is broken, the increase in pressure is not sufficient to extinguish the arc. In this case the 45 extinction of the arc is effected by means of the movable insulating pin 9 which follows the contact 2 into the switch tube 7. This pin reduces the cross-sectional area of the passage through which the gases escape from the auxiliary chamber 50 8 and thereby increases the flow at lower pressures. At the same time the available path for the arc through the tube 7 is restricted and the arc is thereby brought into more intimate contact with the walls which consequently cool 55 it to a greater extent and de-ionise it. Also the quantity of gas which is given off from the walls and from the filling piece 9 is increased owing to the intimate contact with the arc. Therefore, with this arrangement a circuit carrying 60 a small current can also be broken with certainty.

The dimensions of the springs 10 are such that, taking into account the speed at which the contact 2 moves when the circuit is disconnected, 65 the filling piece 9 is accelerated more slowly than the contact 2 and therefore follows it at a certain distance. This has the advantage that, in the case of large currents, during the extinction process or approximately during this process, 70 the full cross-sectional area of the pipe 7 is at first available for the escaping gases whereby too great an increase of pressure in the switch tube and the auxiliary chamber 8 is avoided. The fact that the pressure of the arc opposes the 75

movement of the insulating piece 9 assists this action still further. The movement of the filling piece 9 is therefore made dependent upon the current. Heavy currents are therefore extinguished at the full cross-section of the switch tube and, owing to the filling piece, the arrangement which is dimensioned so as to be suitable for the extinction of arcs produced by heavy currents is capable also of extinguishing to the best 10 advantage arcs due to small currents.

When the connections are restored the switch member 2 returns the filling piece into its original position. On disconnecting the circuit the filling piece follows the switch member but at a certain 15 interval which depends on the strength of the current. It is also possible to move the filling piece in the case of multi-phase circuit-breakers by means of a common earthed operating rod. The movement of the filling piece may then be 20 released by the disconnecting movement at a suitable later time or the operating member of the filling piece may be moved with the operating member of the circuit-breaker after the latter has moved a certain distance.

Figure 2 shows a form of construction which is similar to Figure 1 which is suitable both for switches separating under load, switches with visible point of interruption for disconnecting the normal load, and also for overload-current power 30 switches. The insulating filling piece 9 is rigidly connected with the switch pin 2 and forms a prolongation of the pin. The filling piece 9 may contain a metal insertion 21 whereby the foot of the arc which, on disconnection, is seated on 35 the arcing ring 22, is relieved from the influence of the electric field. The ring 22 is preferably made of a difficultly fusible material, for example of tungsten or a tungsten alloy. The insulating pin 9 is located, when the circuit is connected, in the auxiliary chamber 8 which is made 40 as narrow as possible. Here again, the tube 7 and chamber 8 define a blind passage. The body 5 of the switch tube, the stationary contact 1, and the lead or terminal 4, are carried by a metal body 45 23 which forms the auxiliary chamber 8 and is itself fixed and insulated from earth by means of the insulator 18. On disconnecting the switch, the movement takes place in an upward direction, that is to say in the opposite direction to 50 the direction of movement in Figure 1, otherwise however the construction and the method of operation is similar. The switch tube 7 is provided at the outlet end with a nozzle-like widened opening which increases the velocity of flow of 55 the gases and simultaneously facilitates the introduction of the switch pin when making the connection. The tube 7 may be also of considerably more slender construction than is illustrated in the drawings.

When, on breaking the circuit, the insulating filling piece 9 enters the tube 7, the arc is constrained to burn in the narrow annular space between the insulating pin 9 and the wall 7 whereby an effective extinction is produced. The 60 switch member may be drawn out to such a distance, as is illustrated by dotted lines at 9', that a free air gap is formed.

Since it is possible to increase the formation and energisation of the gas by causing the arc 65 to burn for a longer period in the closed switch chamber, that is to say by moving the switch member more slowly, it is advantageous, in the case of circuit-breakers in which an increased extinguishing action is desired, to design the 70 device so that the switching velocity is low,

namely about 1-3 meters per second, before the extinguishing blast occurs and to increase it, if desired, after extinction in order to obtain better throttling. This method is particularly advantageous in the case of circuit-breakers which 5 have not to disconnect very heavy currents, for example switches separating under load. It is advantageous to increase the switching velocity with the current so that with heavy currents it is high and with small currents it is low. This 10 can be effected by means of additional electro-magnetic forces or by the pressure of the gas itself. In particular the movable contact piece can be pressed upwardly like a piston by means of the pressure produced in the chamber. If the 15 cross-section of the pin is sufficiently great and the volume of the chamber is sufficiently small, the latter arrangement is the simplest if the pressure is suitably high.

Since when breaking a circuit which carries 20 only a small current the auxiliary chamber is not necessary and may even impair the extinguishing conditions owing to the effect which it has in reducing the pressure, it is preferable to cut it off from the switch tube when disconnecting a 25 circuit carrying a small current. For this purpose the filling piece can tightly shut off the auxiliary chamber from the switch tube at the beginning of the extinction of the arc in the case 30 of a circuit carrying a small current. In the case 35 of switches separating underload, the chamber in which the contacts, the filling piece and so forth are located is preferably made as narrow as possible.

In Figure 3 the insulating pin 9 which is made 35 of a material which gives off gas is stationarily arranged inside the hollow movable switch member 2. The walls of the tube 7 are likewise made of a material which gives off gas but may, however, also be made of a material which does not 40 give off gas. In order that the arc may embrace the filling piece 9, the latter may contain an iron insertion. Since the filling piece can be easily replaced it may be made of a material which is eaten away by the arc in a short time. On the 45 disconnecting movement of the tubular switch member 2 which takes place in an upward direction, a free annular space is formed between the switch tube and the filling piece 9 into which space the arc is drawn. The method of operation 50 is therefore the same as in the case of the circuit-breaker shown in Figure 2 with the only difference that the filling piece remains continuously in the switch tube. The height of the filling piece is determined by the required duration 55 of the development of gas as well as by the conditions of flow. The length illustrated in which the filling piece extends into the nozzle-like widened opening of the switch tube 7 produces a particularly advantageous flow of gas in the 60 annular cross-section.

In the concentric arrangements which have hereinbefore been described the position of the path of the arc is fixed only in the longitudinal direction. Since the arc tends to maintain its 65 approximately circular section, it does not, for example, fill up the annular cross-sectional opening which is available for its passage but concentrates at one place. Under the influence of the current conductors and electro-dynamical forces 70 it will generally prefer to take up, according to the current conductors and magnetic conditions in its vicinity, one position which is more strongly attacked than others. With a concentric arrangement a large part of the annular cross- 75

section is left free as has been previously mentioned. The gas in this part is not energised to any considerable extent either by the arc or by radiation or by conduction. Therefore, an arrangement is to be preferred in which the arc is constrained to burn at a definite place in the periphery of the tube. This object can be attained either by arranging insertions of a magnetic material in the wall of the switch tube or by an asymmetrical arrangement of the filling piece. Figures 4 and 5 illustrate arrangements of the latter kind.

As may be seen from the drawings in this form of construction which is otherwise similar to that of Figure 2, the filling piece 9 which is rigidly connected with the switch pin 2 is provided over a certain part of its length with a groove 31 so that an approximately circular free space is formed by the filling piece and walls 7 of the switch tube in which the arc is trapped. When, on breaking the circuit, the filling piece 9 enters the switch tube 7, the said circular cross-sectional space remains free for the passage of the arc and the gases which escape after the switch member 2 has moved out of the tube 7. The arc is therefore quickly extinguished when a circuit carrying a heavy current is broken. The arc itself remains in the groove. The gases from the arc, however, enter into the annular cross-sectional space and produce an additional formation of gas therein. It is further advantageous to provide two or more grooves which are separated by means of ribs. The arc burns in one groove which can also be determined by the breaking place of the contact. The gases from the arc, however, pass through the annular space into the other grooves so that there the pressure gas can flow into the auxiliary chamber. Experiments have shown that with grooves of 10-50 mm² even the smallest currents can be extinguished if the switch tube is about 100 mm. long. The greater the cross-section the longer must the tube be.

This arrangement is particularly advantageous if no very great currents have to be extinguished, for example in the case of switches separating under load and switches for particularly high voltages and so forth. If an air gap is to be provided in such switches then, if the switch member is connected with the filling piece, the latter must be drawn out with the switch member. The extinction of weak current arcs is effected owing to the fact that in the further course of the switching movement the lower ungrooved end of the filling piece 9 almost completely fills the cross-section of the switch tube and thereby quenches or extinguishes the arc to a certain extent. Owing to the fact that the filling piece and the wall of the switch tube are made of substances which give off gas, these parts are protected from being destroyed by the arc because the gases and vapours which are evolved form a heat-insulating layer for the adjacent surfaces.

In the construction according to Figure 6 the filling piece 9 is stationary and an outlet passage 11 for the gases and vapour is provided similarly as in Figure 1. The special feature of this form of construction is the arrangement of an additional flap 35 which, under the action of the spring 36, closes the opening 38 through which the switch member 2 moves out of the body of the switch when the switch member has left this opening. This causes the arc to be lengthened and drawn-in to a greater extent and affords an additional security for the extinction of the arc and for the prevention of blow-backs since no hot gases are

able to follow the switch member when it moves out of the opening 38. The flap 35 is also made of an insulating material which gives off gas for the purpose of increasing its life and producing a better extinguishing effect. The outlet passage 11 is provided in this case with a separate cooling device which consists of metal partitions or the like and simultaneously acts as a silencer.

In Figure 7 one wall 40 of the switch tube 7 which is of rectangular cross-section is pressed by means of springs 41 against the switch member 2 or the insulating piece 9 in order to compensate for any material which is burned away or for other inaccuracies. The free space remaining between the insulating piece 9 and the wall 40 may be of any desired shape, for example of U-shape, of cross shape, or of double T-shape or of E-shape. In particular its cross-section can be reduced practically to zero by pressing the part 40 over its full width against the filling piece 9, since it also possesses the full width of the switch tube. By the term "width" is meant the distance in the direction at right-angles to the plane of the drawings. The actual switch chamber then depends on the counter-pressure of the arc since when the current is large the part 40 is pressed outwards with a greater pressure than when the current is small.

In Figure 8 the currents are heavily damped by connecting a resistance 46 in series in the circuit to be interrupted so that a circuit carrying only a small current can always be broken. During the first part of the switching movement the arc is taken by the switch member 2 to the intermediate contact 47. On the passage of the current through the zero point the arc is extinguished between the contacts 1 and 47 and as the tension of the arc is already high owing to the formation of gas in the tube 48, is not again ignited. Then the extinction takes place in the manner previously described in the form of a small current extinction in the switch chamber which is formed by the switch tube 7 and filling piece 9.

In Figure 9 the cross-section of the insulating filling piece 9 gradually increases whereby the transition from heavy current to low current extinction takes place gradually. The lengths of the insulating piece and so forth can be considerably greater than is illustrated in the drawings with the same cross-sectional dimensions. The switch member is provided with points 50 made of a difficultly fusible metal such as tungsten or the like whereby the formation of metal vapour is greatly reduced.

The filling piece 9 is porous and dips into a liquid 51 which is contained in the auxiliary chamber 8. Preferably the liquid is separated by an intermediate partition 52 from the actual auxiliary chamber 8 in order to prevent it from being thrown about. The level of the liquid can, however, also be so high that two contacts are immersed. The liquid which is drawn up by the filling piece 9 is evaporated in the switch tube 7 by the action of the arc so that the walls of the switch chamber need not give off any gases. The liquid also acts at the same time as a lubricant for reducing mechanical friction.

In Figure 10 there is a stationary filling piece 9 and a tubular switch member 2. The filling piece 9 is porous and impregnated with liquid 70 which can be drawn from the container 51. In order to enable the liquid to be drawn upwards more easily the filling piece 9 is provided with an axial bore into which wicks 55 projects from the liquid 51. In many cases the capillary ac-

tion of the porous filling piece 9 is itself sufficient to draw up enough liquid.

Figure 11 shows a form of construction of the circuit-breaker according to the invention which has particular advantage both mechanically and also in respect to the conduction of the gases. The arrangement shown is of particular advantage when the filling piece has to follow the switch member at a certain distance after it. 5 As distinguished from the arrangements which have been previously described, in this case both these parts are stationary and the switch chamber together with the auxiliary chamber and the ring contact are moved. The switch member 2 is structurally connected with the cooler or silencer 37. The movable part of the switch which consists of the switch tube 7 and the auxiliary container 23 moves downwards, when the circuit is broken, in the gas escape tube 56 which 10 is at the same time provided with the lead or terminal 14 of the switch member 2 and may, for example, be made of hard paper, into the guide body 57 which also serves for conducting the current. For operating the switch a lever 15 16 is provided. The filling piece 9 is carried by a pin 58 which is introduced tightly at 59 into the auxiliary chamber container 23. On the downward movement of the switch part 7-23, the opening 7 is freed by the switch member 2 when the blast occurs. The gases produced flow 20 freely through the tube 56. A special feature of this form of construction is the metallic pin 60 with which the filling piece 9 is provided and which is at the same potential as the contact 1 of the auxiliary chamber and on passing through this contact relieves the foot of the arc attached thereto from the electric field when the current passes through the neutral point. The reference numeral 12 represents a sliding contact which 25 passes the current from the metal casing 23 which carries the contact 1 to the metal casing 57 which is provided with the terminal 4.

The particular advantages of the arrangement according to Figure 11 are that the filling piece 45 9 and the switch member 2 are at a constant distance apart and the intermediate space is free from connecting or fastening members. The result of this is that the cross-section of the switch tube 7 is at first entirely freed after the switch member 2 has moved out of it so that 50 large currents can be extinguished or disconnected without an excessive rise in pressure occurring. Only then is the insulating piece 9 inserted into the switch tube 7 for extinguishing small currents.

55 In the arrangement according to Figure 12 the auxiliary chamber 8 is provided with a separate opening 65 for the blast. The chamber 8 is also connected, as in the other arrangement, with the switch tube 7. The switch member 2 is moved into the tube 7 after the separation of the contacts while the filling piece 9 follows it directly, as illustrated, or at a distance. The extinction in this case also takes place by allowing the blast 60 to escape out of the tube and the auxiliary chamber 8. In this case, however, the blast is set free by the filling piece 9 which at the moment when the pressure is produced closes the nozzle-like blow-off opening 65. This nozzle-like 65 opening may be made of insulating material as is illustrated in the drawings. If this is the case the arc is formed into a loop under the influence of the blast. The entire nozzle can also be made of metal. Then one foot of the arc moves from the stationary contact 1 through

the nozzle upwards. The contacts themselves may tightly close the opening 65 in particular when the movable contact 2 is resiliently constructed. The auxiliary chamber 8 need not necessarily surround the switch tube 7. The arrangement which has been illustrated has, however, the advantage that, on the switching movement, an increase of pressure takes place both on the inside and the outside of the tube so that the tube is subjected to much less stress 10 owing to the increase of pressure within it than if it were surrounded by the atmosphere. It is even possible to provide in the tube openings for relieving the pressure in order to reduce the pressure in the interior of the tube to the pressure 15 in the auxiliary chamber. Care must, however, be taken by providing projections, screens or the like, that the arc cannot strike around the tube. This arrangement of the auxiliary chamber can also be employed in the other forms of construction 20 of the invention.

An insulating tube 66 which at the same time carries the switch body 67 can be employed in order to conduct additional gas under pressure to the switching place from the outside in such a 25 way that both blasts take part simultaneously in the extinction of the arc. In order to extinguish the arc it is sufficient to move the switch member to the position of the insulating filling piece 9 which is indicated in dotted lines at 9'. 30 An air gap can also be provided by a completely drawing out the switch member with the insulating piece. An arrangement in which the insulating piece 9 remains in the tube while the switch member 2 is moved at the separating distance is, however, preferable. On breaking the circuit, the foreign gas can be mechanically compressed and can be used for the extinction of small currents since from the auxiliary chamber, which may in some cases also act as a gas- 35 compression cylinder, it extinguishes small current arcs after the blast has been released. The switch tube and the filling piece are regulated relatively to one another in such a manner that they control the currents above them up to the 40 45 limit. Small quantities of gas at low pressure are sufficient. If the blast with the foreign gas takes place after the extinction of large currents, for example owing to the filling piece releasing the inlet opening in the auxiliary chamber, it 50 then acts to clean the switch gap.

It is sufficient if the foreign gas is employed for extinguishing purposes only with large currents for the purpose of increasing the power of the switch. Smaller currents are then 55 extinguished in the manner described by means of the co-action of the switch tube with the filling piece. A reduced blast may then pass in particular in cases where the current is heavy. The stream of cold foreign gas protects the walls from 60 giving off too much gas. The invention can also be used with advantage for switches or circuit-breakers for lower voltages, for example for motor switches, installation switches and the like.

Figure 13 shows a form of construction with series switching of two switch points which are of exactly similar construction. Each switch point is provided with a supporting insulator 70 which is mounted on a common base plate 71 70 and carries the switch chamber. This consists of a metal intermediate piece 69 which carries the lead or terminal 72 and the fixed contact 73 and of the switch tube 74 as well as the filling piece 75, both of which are likewise fixed to the inter- 75

mediate piece 69. The two movable switch members 76 are connected together by a cross-piece 77. Since the two switch members are at the same potential, the streams of gas escaping from the two switch tubes can strike in common the cross-piece 77. It is only necessary to provide partitions 78 between the switch points of different phases which, looking in the direction of the person viewing the figure, are to be considered to be situated one behind the other. The switch is driven by means of a rod 79 and crank 80 from a shaft 81 which is driven in any desired manner.

If the filling pieces are not stationary but are movable, for example in the manner indicated in Figure 1 or Figure 2, the insulators 70 can simultaneously form the auxiliary chambers (pressure accumulating chambers).

The form of construction shown in Figure 14 is specially suitable for high voltages and not very heavy currents, for example for switches separating underload. On the base plate 71 is mounted the insulator 70 which carries the fixed contact 73 together with the lead or terminal 72. The reference 74 represents the switch tube, 76 the movable contact which is connected with the insulating filling piece 75. The latter is acted upon by a compression spring 85. A stop 86 limits the travel of the switch member 76 since after a certain switching travel it abuts against the contact 73. The upper end of the switch member 76 carries a radiation cap 87 and an air contact 88. The corresponding switch knife is revoluble about an axis and is mounted by means of a metal piece 91 with a lead or terminal 92 on a supporting insulator 93. The drive is effected by means of a rod 79 and crank 80 from a shaft 81.

In the connected position, the current flows from the terminal 72 over the contacts 73 and 76 to the air contact 88 and thence by way of the switch knife 89 and the part 91 to the terminal 92.

On breaking the circuit, the switch arm 89 is moved upwards by the driving rod 79. Since the spring 85 pushes the switch member 76 and the filling piece 75 after it, the connection between the contacts 88 and 89 is at first maintained and the circuit is broken between the contacts 73 and 76. The filling piece 75 is pushed into the switch tube 74 until the stop 86 prevents the further movement of the parts 75 and 76. Then the switch arm 89 alone moves further and is thereby separated from the contact 88. There are, therefore, formed two arcs connected in series. The arc which burns in the tube 74 is extinguished whereby the arc burning in the atmosphere is also extinguished. By this means with a relatively small length of the switch tube a large air gap is procured. The stop 86 is of piston-like construction and, on its upward movement, reduces the size of the pressure-accumulating chamber 94 located above it. By this means the blast effect of the gas flowing through the switch tube 74 is intensified and the extinction of the arc is correspondingly improved. The radiation cap 87 simultaneously serves as a deflector for the escaping gases and keeps them away from the air contacts 88 and 89. In the disconnected position the parts 88 and 89 assume the position indicated in dotted lines by the references 88' and 89'.

The invention is not, of course, limited to the constructional examples shown in the drawings but can be modified as desired. It is also pos-

sible to use another pressure medium for extinguishing the arc instead of the gases or vapours, for example an insulating liquid. The processes for extinguishing the arc then take place within the liquid from which the extinguishing gases and vapours are produced. In this case, therefore, the production of gas from the walls of the switch tube or of the filling piece are only necessary when it is to be used for protecting the insulating parts from being attacked by the arc. In liquid switches the lower limiting current of the switch tube is lower than is gas switches. An insulating piece is, therefore, generally sufficient which only partly reduces the bore of the tube. The process according to the invention facilitates the construction of liquid switches for high voltages.

Each form of the invention contains what has been termed for convenience, a blind passage, defined by the switch tubes and their adjoining chambers. The significance of this term is a passage closed at one end permitting the accumulation of pressure.

I claim:

1. A circuit breaker comprising a housing having a gas evolving wall and defining a passage, said housing being substantially closed to atmosphere during closed circuit conditions, said housing containing a gas accumulating chamber, a conductive electrode closely fitting said passage in said housing and freely relatively removable with respect to said housing, an insulating member imposed in said passage to limit the size of said passage, and a pair of terminals interconnected by said electrode during closed circuit conditions.

2. A circuit breaker comprising a housing containing gas evolving material, said housing being substantially closed during closed circuit conditions and defining a passage, a conductive electrode penetrating and closely fitting a passage in the housing, said terminal enclosed by said housing for rubbing contact with said electrode, said housing defining a switching chamber adjacent to said terminal, said electrode and housing being relatively longitudinally movable and an insulating member imposed in said passage to limit the volumetric content of said passage.

3. A circuit breaker comprising a housing containing gas evolving material and defining a blind passage but otherwise closed to atmosphere, a terminal in said housing, a conducting electrode penetrating and closely fitting said passage and contacting said terminal during closed circuit conditions, said housing containing a gas accumulating chamber, means for relatively separating said electrode and housing to open said housing to atmosphere during open circuit conditions and an insulating member imposed in said passage for restricting the sectional area of said passage.

4. A circuit breaker comprising a housing containing gas evolving material and defining a blind passage but otherwise closed to atmosphere, said housing containing a gas accumulating chamber, a conducting electrode closely fitting said passage and penetrating said housing during closed circuit conditions, means for relatively separating said electrode and housing to open said housing to atmosphere during open circuit conditions and an insulating member for restricting the sectional area of said passage, said insulating member having an actuating means separate from that of said electrode.

5. A circuit breaker comprising a housing con-

taining a blind passage and being otherwise closed to atmosphere, gas evolving material in said housing, a conducting electrode closely fitting said passage and penetrating said housing during closed circuit conditions, said housing containing a gas accumulating chamber, means for relatively separating said electrode and housing to open said housing to atmosphere during open circuit conditions and an insulating member for restricting the sectional area of said passage, said insulating member and said electrode having a common actuating means.

6. A circuit breaker comprising a housing, gas evolving material and in which a blind passage is defined the housing being otherwise closed to atmosphere, a conducting electrode closely fitting said passage and penetrating said housing during closed circuit conditions, said housing containing a gas accumulating chamber, means for relatively separating said electrode and housing to open said housing to atmosphere during open circuit conditions and an insulating member for restricting the sectional area of said passage, said insulating member being fixed with respect to one of the relatively moving members.

7. A circuit breaker comprising a housing defining a blind passage and being otherwise closed to atmosphere, a conducting electrode closely fitting said passage and penetrating said housing during closed circuit conditions, said housing containing a gas accumulating chamber, means for relatively separating said electrode and housing to open said housing to atmosphere during open circuit conditions and an insulating member imposed in said passage for restricting the sectional area of said passage, said passage having a wall of gas evolving material.

8. A circuit breaker comprising a housing containing a blind passage and being otherwise closed to atmosphere, a conducting electrode closely fitting said passage and penetrating said housing during closed circuit conditions, said passage containing a gas accumulating chamber, means for relatively separating said electrode and housing to open said housing to atmosphere during open circuit conditions and an insulating member imposed in said passage for restricting the sectional area of said passage, said insulating member having a wall of gas evolving material.

50 9. A circuit breaker comprising a housing containing a blind passage and being otherwise closed to atmosphere, a conducting electrode closely fitting said passage and penetrating said housing during closed circuit conditions, said housing containing a gas accumulating chamber, means for relatively separating said electrode and housing to open said housing to atmosphere during open circuit conditions and an insulating member imposed in said passage for restricting the sectional area of said passage, said insulating member and a wall of said passage being composed of a gas evolving material.

10. A circuit breaker comprising a housing which is substantially closed during closed circuit conditions and containing a passage, a conductive electrode closely fitting said passage in the housing, gas evolving material in said housing, a terminal enclosed by said housing for rubbing contact with said electrode, said housing defining a switching chamber adjacent to said terminal, said electrode and housing being relatively longitudinally movable and an insulating member imposed in said passage to limit the volumetric content of said passage, said insulating member being actuated to move into said switching chamber during a break of the circuit. 5

11. A circuit breaker comprising a housing having a gas evolving wall and defining a passage, said housing being substantially closed to atmosphere during closed circuit conditions, a conductive electrode closely fitting said passage in said housing and freely removable out of said passage, 20 a pair of terminals interconnected by said electrode during closed circuit conditions and an insulating member limiting the size of said passage after the circuit is broken.

12. A circuit breaker comprising a terminal 25 and an electrode, a housing containing a gas evolving material and defining a passage for the reception of said electrode to close said housing to atmosphere during closed circuit conditions, means for completely separating said housing and 30 electrode during a circuit breaking operation to release to atmosphere gas generated by the arc, said housing and its passage being so conformed as to direct all of the generated gases to follow the arc until the separating movement has 35 opened the housing to atmosphere, and an insulating element having a smaller volumetric displacement than said electrode imposed in the path of the arc.

13. A circuit breaker comprising a housing defining a passage, a closely fitting electrode received within said passage and closing the same under circuit making conditions, a pair of terminals interconnected by said electrode during closed circuit conditions, one of said terminals 45 being located within said housing, means for relatively moving said electrode and housing during a circuit breaking operation to expose the resulting arc to a gas evolving material and to subsequently open said passage to atmosphere. 50

14. A circuit breaker comprising a housing having a gas evolving wall and defining a passage, a hollow conductive electrode closely fitting said passage in said housing, closing the housing under circuit making conditions and freely removable 55 out of said passage, a pair of terminals interconnected by said electrode during closed circuit conditions and a member of gas evolving material within said hollow electrode for increasing the active gas evolving surface after the circuit is 60 broken.

SIGWART RUPPEL.

CERTIFICATE OF CORRECTION.

Patent No. 2,152,283.

March 28, 1939.

SIGWART RUPPEL.

It is hereby certified that error appears in the printed specification of the above numbered patent requiring correction as follows: Page 6, second column, line 41, claim 2, for "a passage" read said passage; line 42, same claim, for "said terminal" read a terminal; and that the said Letters Patent should be read with this correction therein that the same may conform to the record of the case in the Patent Office.

Signed and sealed this 6th day of June, A. D. 1939.
